PRECISION FOCUSING ADJUSTMENT FOR PHOTOGRAPHIC RECORDING APPARATUS

David G. Fladlien, Los Angeles, and Perry J. Smith,
Hawthorne, Calif., assignors to Space Technology Laboratories, Inc., Redondo Beach, Calif., a corporation of Delaware

Filed May 24, 1963, Ser. No. 75,048

Term of patent 14 years

(Cl. D61—1)

Fig. 1.

Fig. 2.

FIG. 1 is a rear pictorial view of a precision focusing adjustment for photographic recording apparatus showing our new design; and

FIG. 2 is a front pictorial view thereof.

The fragmentary broken-line showing of an oscilloscope in FIG. 1 is for illustrative purposes only.

We claim:

The ornamental design for a precision focusing adjustment for photographic recording apparatus, substantially as shown and described.
